UNITED STATES PATENT OFFICE

155,844

DESIGN FOR A BILLFOLD

James C. Simpson, Hartford, Wis.

Application May 5, 1949, Serial No. 2,450

Term of patent 14 years

(Cl. D87—3)

To all whom it may concern:

Be it known that I, James C. Simpson, a citizen of the United States, and resident of Hartford, in the county of Washington and State of Wisconsin, have invented a new, original, and ornamental Design for a Billfold, of which the following is a specification, reference being had to the accompanying drawing, forming a part thereof.

Fig. 1 is an elevational view of one side of the billfold showing my new design.

Fig. 2 is an elevational view of the other side thereof.

I claim:

The ornamental design for a billfold, substantially as shown.

JAMES C. SIMPSON.
